* Attorney

UNITED STATES PATENT OFFICE.

NELL FULTON, OF NEW YORK, N. Y.

WAVE PRESERVER.

Application filed July 9, 1928. Serial No. 291,451.

My invention relates to devices intended particularly for preserving waves so that it is not necessary to repeat the waving operation as often as is customary when no wave preservers are employed.

The primary object of my invention is the provision of a device which may be slipped into place and clamped on the wave to thus preserve the form of the wave.

10 It is especially my object to provide a structure of the kind specified which may be applied quickly and without difficulty.

Another of my objects is the provision of a structure of extreme simplicity which may be 15 made and sold at a low cost.

Having in view these objects and others which will be pointed out in the following description, I will now refer to the drawings, in which—

20 Figure 1 is an illustration showing my wave preserver in its open position and

Figure 2 is an illustration of the same wave preserver in its closed position.

Figures 3 and 4 illustrate the use of the 25 wave preserver.

The base portion 10 of the wave preserver is somewhat elongated and it is provided with a slot 11 at one end and with a tapered point 12 at the other end. The base 10 is formed 30 out of any material which possesses sufficient rigidity and it is preferably formed from material having a certain degree of resiliency. Sheet steel is admirably adapted for this purpose but it is obvious that celluloid, rubber or even fiber board may be employed. The latter 35 three of these materials have the advantage of being inactive chemically in the presence of moist hair. Should material like sheet steel or sheet brass be used in the construction of

40 the base, it is desirable that the material be treated to prevent its staining the hair. The base should be curved slightly from end to end to more or less fit the contour of the head.

Secured to the base 10 through the slot 11 45 is a strip 13 of elastic webbing and this strip is provided at its free extremity with an engaging member 14, the end of the strip passing through a slot 15 in the engaging member and being stitched in the same manner at both 50 ends of the elastic strip. The engaging member 14 is formed from material which is similar to that of the base 10 and it is provided with a pair of ears 16 which are lapped over

to provide a socket for the tapered end 12 of the base 10. The engaging member 14 is also 55 provided with a handle member 17 for convenience in pulling the engaging member 14 into engagement with the tapered end 12.

The use of the device will be obvious from an inspection of Figures 3 and 4. It is only 60 necessary to slip the base portion 10 beneath the wave on the side next to the scalp and then to grasp the handle member 17 to stretch the webbing 13 and to force the engaging member 14 over the tapered end 12 of 65 the base. The requisite number of wave preservers should be applied so as to clamp all of the waves or at least to clamp those waves which are liable to be flattened out during slumber or at other times.

I have shown and described connections between the base member 10 and the elastic member 13 but it is obvious that the same result could be accomplished by any of other numerous forms of connections. It is desirable in order to prevent misplacement of the parts that one of these connections be permanent, and in order to function properly it is necessary that the other connection be releasable. Any form of permanent connection at 80 one end of the clamping members and any form of releasable connection at the other end will therefore fall within the spirit and scope of my invention.

Having thus described my invention in 85 such full, clear, and exact terms that its construction and operation will be readily understood by others skilled in the art to which it pertains, what I claim as new and desire to secure by Letters Patent of the United States 90 is:

A wave preserver adapted to be clamped to hair waves to preserve the form thereof, said wave preserver including an elongated base member of bowed form, an elastic strip 95 on the convex surface of said base member, said elastic strip being secured at one extremity to an end portion of said base member and having means at the free extremity for engaging the free end portion of said 100 base member with the wave clamped therebetween, said elastic strip being under tension when it is in clamping relation with said base member.

In testimony whereof I affix my signature.
NELL FULTON.
